UNITED STATES PATENT OFFICE.

PETER M. BOECK, OF GRAND HAVEN, MICHIGAN, ASSIGNOR, BY MESNE ASSIGNMENTS,
TO JOACHIM R. M. KNUDSEN, OF MUSKEGON, MICHIGAN.

METAL WINDOW.

Application filed October 4, 1926. Serial No. 139,249.

This invention relates to a metal window and is particularly concerned with a novel means for latching a screen in the window, which means may be operated from either 6 the inside or outside, thereby permitting the removal of the screen from either side when it may be desired.

A further object and purpose of the invention resides in the provision of means 10 whereby a metal window may be constructed which may be held in closed position, tilted outwardly to partially open position or elevated bodily to an upper fully open position, the invention which I have 15 made in connection with a window of this character being a very simple means whereby the window sash may be very simply and readily removed and detached from its casing, this many times being very desirable 20 particularly in the summer time when the screen is used. Various other objects and purposes than those stated will appear as understanding of the invention is had from the following description taken in connection 25 with the accompanying drawing, in which,

Fig. 1 is an elevation of the window from the inner side thereof, certain parts being broken away and shown in section for a 30 better disclosure.

Fig. 2 is a vertical section on the plane of line 2—2 of Fig. 1, the window being shown in closed position and the screen being therein.

Fig. 3 is a vertical section on the plane of line 3—3 of Fig. 1 showing the window tilted to partly open position.

Fig. 4 is a similar sectional view illustrating the window removed from its frame or 40 casing.

Fig. 5 is a fragmentary enlarged horizontal section on the plane of line 5—5 of Fig. 1.

Fig. 6 is a fragmentary vertical section 45 through the upper part of the screen and of the window casing showing how the latching means for the screen is used, and

Fig. 7 is a fragmentary enlarged elevation of the construction shown in Fig. 6.

Like reference characters refer to like 50 parts in the different figures of the drawing.

The outer casing or frame of the window is of metal and includes vertical ends of substantially Z-shape having a web 1, an 55 outwardly extending flange 2 at the inner side of the window and an inwardly extending flange 3 at the outer side, best shown in Fig. 5. The bottom rail of the casing is also of metal including an inner downwardly extending flange 4, a horizontal ledge 5 bent outwardly from the upper edge thereof from which a vertical section 6 is turned downwardly for a short distance and then the metal again bent outwardly making the horizontal section 7, as shown in Figs. 2, 3 and 4. The upper rail includes an inner vertical flange 8 with a horizontal section 9 bent outwardly from the lower edge thereof, it in turn being bent downwardly making a vertical section 10, again outwardly to make the horizontal section 11 and terminating in a downturned outer flange 12, fully shown in the same figures. These parts are welded together so as to 75 make a permanent and rigid connection.

Against the inner side of the flange 3 of each of the vertical end members of the frame a sheet metal track member is located and permanently secured, the same comprising a web 13 which parallels and is spaced inwardly from the web 1, it having an inturned outer flange 14 which lies against and is welded or otherwise permanently secured to the flange 3, as shown in Fig. 5. At its inner edge a track 15 is bent outwardly from the web 13, this track lying at an incline to the vertical, as shown. Adjacent its lower end but a short distance above the same track 15 is cut away partly 85 making the notch or opening 16, the purpose of which will later appear.

A screen 17 in a rectangular frame 18 may be placed in the frame thus made, its ends lying back of the flanges 14 previously 95 described, while its upper bar lies back of the downturned outer flange 12 of the upper rail of the window frame or casing. Midway between its ends the screen is provided with a vertical bar 19 which serves to strengthen and reinforce the same and also furnish a support for the latch. A pin 20 having a head identical with a screw head so as to receive the end of a screwdriver 100

passes through the bar 19 near its upper end and is permanently secured to a latching clip 21 which lies at the outer side of the screen. This latching clip when turned to 5 upper position lies against the outer side of the flange 12, the upper rail of the frame 18 of the screen being at the inner side of said flange. In this way the screen may be securely held in place.

10 It is evident that the clip 21 may be engaged by the fingers from the outside of the window and turned to a position where it disengages from the flange 12 whereupon the screen will be disconnected and may be 15 removed, particularly if the window, which will later be described, has been removed from the frame. It is also evident that by using a screwdriver or similar tool the head of the pin 20 may be engaged and the pin turned 20 whereupon the clip rigidly secured to the pin will also turn and thus free the screen. The engagement of the head of the pin 20 is from the inner side of the screen so that with this construction the screen may be unlatched from either side.

25 The window sash is also formed of metal and includes an upper horizontal rail 22 of angle form, a lower rail 23 of Z-bar formation, a plurality of vertical partitions 30 24 disposed between the upper and lower rails and two vertical ends of special form best shown in Fig. 5. These ends of the window sash include a vertical web 25 which lies just within the web 13 of the member at 35 each end of the casing. An inturned flange 26 is made at one edge of the web 25 against which, as well as against the flanges of the partitions 24 and the upper rail 22, the glass panes of the window bear. At the 40 opposite inner edge of the web 25 the metal is turned outwardly for a short distance at right angles making the section 27 and is then turned back at right angles to make the section 28 which passes between the web 1 and the track 15 at each end of the window. 45 Each of the sections 28 at each end of the window sash is equipped with a pin or roller 29 extending inwardly near the lower outer corner of said section 28. These rollers or 50 pins lie back of the tracks 15. When the window sash is tilted outwardly, as shown in Fig. 3, they serve as stops when brought against the tracks 15. When the window is bodily elevated upward these members 29 55 ride on the tracks 15 and help to hold the window in upper position bearing against the track at one side while the lower portions of the sash bear against the track at the opposite side thereby gripping the 60 tracks and holding the sash in upper elevated position. It is also evident that by bringing the members 29 to the notches or openings 16 the sash may be bodily removed from its casing or frame, as shown in Fig. 65 4. This is a very simple and practical way

of providing means for removing the window sash from the frame whenever it is desired, particularly during summer weather.

A latch means for holding the window in closed position is provided. To the upper rail of the casing a flat bar 30 is attached and extends inwardly, its inner end being turned slightly downward. Adapted to engage with this is a latching member 31 connected to the upper rail 22 of the window sash, as best shown in Fig. 2, it being equipped with a finger engaging member 32 so that it may be drawn downwardly to disengage from the bar 31 when the window is to be open. The member 31 is of spring material. The latch provided is effective and very simple to operate.

The construction described for permitting the removal of the window sash and for latching and unlatching the screen from either side of the window so that it may be removed when the window sash has been removed from its casing, while simple in construction is very desirable, necessary and practical. Removal of the screen is many times necessary for the passing of material through the opening provided by the window casing. This is particularly true when fuel is to be placed in the basement, the window described being particularly adapted for basement installation. Both the window sash and the screen should be removed at such times. During summer the window sash preferably will be removed from the frame and the screen will be in place. This screen may be readily removed when needed under such conditions. In the winter the screen will not be in place in the window normally but the window sash will be in place and it can be readily removed for introducing fuel into the basement. Or if both the window sash and the screen are in place both can be easily removed when desired. The invention is defined in the appended claims and is to be considered comprehensive of all forms of structure coming within their scope.

I claim:

1. In a window, an outer casing of metal having vertical ends, guides at each end of the casing inclined slightly to the vertical, each of said guides including a laterally extending flange having a portion thereof cut away near its lower end to form an opening or recess, a window sash mounted within said casing, said sash at each end having a part extending back of the adjacent guide, and a member attached to the lower end of each of said mentioned parts located back of its adjacent guide so that the sash may be tilted or bodily moved upward on said guides or removed from the casing when said members are brought into position to pass through the openings or recesses in the guides.

2. In a window construction, an outer casing, a sash mounted in said casing adapted in closed position to fill the opening therein, means whereby said sash may be tilted away from the casing at its upper end or bodily moved upward and turned to substantially horizontal position when in upper position, interengaging portions of the respective

sash and casing for retaining the sash in its upper substantially horizontal position, 10 combined with means whereby said sash may be disconnected and removed from the casing, substantially as described.

In testimony whereof I affix my signature.

PETER M. BOECK.
